SHEET COLLATING DRUM

Luis Mestre, New York, N. Y.

Application August 23, 1954, Serial No. 31,969

Term of patent 7 years

(Cl. D64—11)

The figure is a front perspective view of a sheet collating drum embodying my new design.

The side, not shown, is like the side shown and the rear is substantially plain.

I claim:

The ornamental design for a sheet collating drum, as shown and described.
